UNITED STATES PATENT OFFICE.

ROBERT L. RAY, OF LENOIR, NORTH CAROLINA.

METALLIC CHAIR.

Application filed April 5, 1924. Serial No. 704,476.

To all whom it may concern:

Be it known that I, ROBERT L. RAY, a citizen of the United States, residing at Lenoir, in the county of Caldwell and State of North Carolina, have invented new and useful Improvements in Metallic Chairs, of which the following is a specification.

My present invention pertains to chairs, and has for its object to provide an inexpensive, neatly appearing and strong chair of metal, and one which is light in weight and is therefore adapted to be handled with ease and facility.

Other objects and practical advantages 15 of the invention will be fully understood from the following description and claims when the same are read in connection with the drawings, accompanying and forming part of this specification, in which:—

20 Figure 1 is a side elevation of the chair constituting the preferred embodiment of my invention.

Figure 2 is a front elevation of the chair.

25 Figure 3 is a top plan view of the chair. Figure 4 is a vertical central section of the chair.

Figure 5 is a horizontal section taken in the plane indicated by the line 5—5 of Figure 4, looking downwardly.

30 Figure 6 is a perspective showing one of the loops comprised in my improvement.

Figure 7 is a detail perspective showing one bolt of the construction and its respective nut.

35 Figure 8 is a detail top plan view of the sheet metal seat comprised in the improvement.

Similar numerals of reference designate 40 corresponding parts in all of the views of the drawings.

Among other elements my novel chair comprises a tubular back member 1, of general inverted U-shape, the lower portions of the sides of said member being flared laterally as best shown in Figure 2 and being also flared rearwardly as shown in Figures 1 and 4. The chair also comprises a tubular front member 2 of inverted U-shape but of considerable less height than the back member 1, the upper portion of which latter is curved slightly rearward as shown in Figures 1 and 4, to increase the comfort of a person occupying the chair.

In addition to the said back and front members 2 the chair comprises side straps 3 and seat supporting straps 4, the seat

which is formed of sheet metal being designated by 5. The side straps 3 are arranged at about the proportional distance illustrated below the seat supporting straps 4 and are provided at their ends with loops 6 which snugly receive the side portions of the members 1 and 2 and are held in a closed state by rivets 7 or other appropriate means. There are two of the side straps 3, and they are connected together through the medium of transverse horizontally disposed straps 8 which are provided at their ends with pendent angularly disposed portions 9 opposed to the inner sides of the straps 3 and riveted or bolted at 10 thereto. Manifestly in virtue of the straps 8 being interposed between and abutting against the straps 3 as illustrated and described the said straps 8 are calculated to effectively brace the 75 straps 3 and in that way contribute materially to the stiffness and strength of the chair as a whole.

The seat supporting straps 4 are provided at their ends with loops 6^a and 6^b which are in close state by rivets 7^a or other appropriate means. It will also be noted that the loops 6^b are notched at 6^c to snugly receive the top bar of the member 2 and that the loops 6^a of the straps 4 are arranged directly above loops 10 on a cross strap 11, the said loops 10 being secured by rivets 12 or other appropriate means around the side portions of the rear member 1, and the strap 11 being twisted as best shown in Figure 3 90 and being provided with an intermediate horizontal portion disposed immediately under and connected at 13 to the rear portion of the seat 5. The said seat 5 is notched at 14 to snugly receive the side portions of the 95 back member 1, and the central portion of the seat 5 is supported by a cross bar 15 interposed between and connected to the upper side straps 4, and connected to the center of the seat 5 by a bolt 16 and nut 17 as clearly 100 shown in Figures 4 and 7. By virtue of this construction it will be manifest that the seat 5 may be expeditiously and easily secured on the chair frame and may as readily be detached therefrom when desired.

In addition to the elements described the chair comprises a back panel 18 of sheet metal, the upper end of the said panel 18 being let into and held by a slot 19 in the upper cross-bar of the back member 1 and being arranged with its lower end interposed and secured between the horizontally dis-

posed portion of the strap 11 and the seat 5 as shown in Figures 2 and 3. Notwithstanding this relative arrangement which provides for the strong connection of the lower end of the panel 8 it will be manifest that when the connections 13 are in the form of bolts and nuts which is within the discretion of the manufacturer, the said connection of the lower end of the panel 18 will 10 not interfere with the detachable characteristic of the seat 5.

As clearly shown in Figure 4 it is within the purview of my invention to slightly dish the sheet metal seat 5 with a view to contributing to the comfort of a person occupying the chair.

I would also have it understood that bolts and nuts may in the discretion of the manufacturer be used at all points in lieu of 20 the rivets described without affecting my invention.

It will be apparent from the foregoing that my novel metallic chair is at once simple and inexpensive in construction and 25 light in weight and that the said chair is susceptible of being handled with the expenditure of little effort and is well adapted to withstand the usage to which chairs are ordinarily subjected and is also well adapted 30 to withstand the water which fits the chair especially for outdoor use.

When deemed expedient the chair may be provided as illustrated with comparatively broad feet 19 of rubber, metal or other appropriate material, the said feet being secured 35 in any approved manner on the ends of the members 1 and 2.

I have entered into a detailed description of the construction and relative arrangement 40 of the parts embraced in the present and preferred embodiment of my invention in order to impart a full, clear and exact understanding of the said embodiment. I do not desire, however, to be understood as confining my 45 self to the specific construction and relative

arrangement of parts inasmuch as in the future practice of the invention various changes and modifications may be made such as fall within the scope of my invention as defined in my appended claim. 50

Having described my invention, what I claim and desire to secure by Letters-Patent, is:—

A metallic chair comprising a back member of inverted U-shape, a comparatively 55 short front member of inverted U-shape, said back member having an upper cross bar and a slot in the underside thereof, lower side straps looped about and connected to the lower side portions of the back and front 60 members, transverse braces interposed between and abutting against and connected to said lower side straps, upper side straps looped about and secured to the upper corner portions of the front member and also 65 looped about and secured to the side portions of the back member and having notches in their forward loops snugly receiving the upper transverse portion of the front member, a back strap looped about and secured 70 to the side portions of the back member and twisted and having a comparatively high horizontally disposed intermediate portion, a transverse strap extending between and connecting to the upper side straps, a seat 75 connected to said transverse strap and supported by the upper side straps and by the comparatively high intermediate portion of the twisted strap, a back panel having its upper end let into the said slot in the upper 80 transverse portion of the back member and also having its lower end interposed between the rear portion of the seat and the comparatively high portion of the twisted strap, and means connecting the said high portion 85 of the twisted strap, the back panel, and the rear portion of the seat.

In testimony whereof I affix my signature.

ROBERT L. RAY.
